UNITED STATES PATENT OFFICE.

JAMES B. MAYBERRY, OF SHREVEPORT, LOUISIANA.

AGITATOR FOR CHAIN PUMPS.

Application filed May 25, 1923, Serial No. 641,350.

To all whom it may concern:

Be it known that I, JAMES B. MAYBERRY, a citizen of the United States, residing at Shreveport, Caddo Parish, Louisiana, have 5 invented a certain new and useful Improvement in Agitators for Chain Pumps, of which the following is a full, clear, and exact description, such as will enable others skilled in the art to which it appertains to 10 make and use the same.

The invention relates to agitating means to be used with chain bucket pumps in operations in oil wells and other deep wells. The device is intended as an attachment for 15 use in connection with the type of bucket chains disclosed in my co-pending application, Serial No. 630,202, filed April 6th, 1923.

The object of my invention is to provide 20 an agitating blade which may be secured upon the chain of a deep well bucket pump and serve to automatically keep the sand and other foreign matter stirred up in suspension so that it may be carried out of the well 25 with the fluid being pumped.

Another object is to provide a weight for 30 the lower end of a chain bucket pump for deep wells which will serve to keep the chain in proper vertical alignment and serve to prevent any kinking of the chain in use.

Referring to the drawing herewith, wherein in a preferred embodiment of my invention is shown, Fig. 1 is a side elevation of my agitator; Fig. 2 is a bottom plan view; 35 Fig. 3 is a side elevation taken at right angles to the view shown in Fig. 1 and Fig. 4 is a transverse section on the plane 4—4 of Fig. 3 showing the yoke alone.

My device comprises a blade section and I 40 have shown this blade in the form of two flat blades 1, crossed at right angles and joined together as shown best in Fig. 2. The upper end of the compound blade 1 thus formed is fixed to a yoke 2 made up of two 45 plates 3 and 4 forked at their lower ends to include the upper end of one of the wings of the agitator and riveted, or otherwise secured, to the opposite sides of one of the wing sections of the blade.

The upper ends of the two plates are 50 rounded off slightly at 5 on the inner faces and a cross pin 6 through said ends furnishes a mounting for a roller bearing sleeve 7 adapted to roll thereon.

The bucket chain 8, shown in Fig. 1 is 55 adapted to be threaded through the upper

end of the yoke 2 and as said chain is operated the weight of the agitator will bear on said chain. The pin 6 is removable and when thus removed the agitator may be 60 readily secured in position.

The weight of the agitator causes it to ride at the lowermost end of the chain and will thus maintain the chain in vertical position. As the chain is customarily made up 65 of long and short links, the agitator will be moved up and down by the running of the chain, thus serving to agitate the sand by the reciprocating action of the sharpened lower end of the blades. This will keep the 70 sand and shale always in suspension in the fluid so that it may be gathered up by the buckets on the chain and carried to the surface and discharged.

The use of this agitator will prevent the 75 clogging of the lower end of the well with sand or shale and materially assist in keeping the well clean and allow the operation of the pump for long periods.

While I have shown and described one 80 particular form of agitator it will be obvious to one skilled in the art that the form may be varied in many respects without departing from the spirit of my invention and I do not wish to be confined to the particular 85 form shown further than is done in the claims appended hereto.

Having thus described my invention, what I claim as new and desire to protect by Letters Patent is:

1. An agitator for chain bucket pumps comprising a downwardly extending pointed blade, a forked yoke thereon to receive said chain and a bearing pin for said agitator at the upper end of said yoke.

2. An agitator for use with chain bucket pumps in deep wells, comprising a blade sharpened at the lower end, a yoke at the upper end to receive said chain, and a cross bearing above said chain having a rotatable 100 sleeve thereon.

3. An agitator for use with chain bucket pumps, comprising a chain engaging yoke and a pointed plate thereon, said agitator adapted to roll on the links of said chain 105 and be thereby reciprocated through the operation of the chain to dig up the material at the bottom of the well.

4. An agitator for use with chain bucket pumps comprising a double blade, two plates 110 secured to the upper end thereof and a cross pin through the upper end of said plates.

5. An agitator for use with chain bucket pumps, comprising an agitating blade, and means to secure said blade to said chain whereby the running of the chain there-through will reciprocate said blade to break up and agitate the sand and other solid material at the bottom of the well.
6. In combination with a bucket chain for

deep well operations, a yoke, a downwardly extending agitator suspended on said chain to ride on the links thereof and to be reciprocated thereby, for the purpose described. 10

In testimony whereof, I hereunto affix my signature this 21st day of May, A. D. 1923.

JAMES B. MAYBERRY.
